UNITED STATES PATENT OFFICE.

FRANCIS O. HELTZEL, OF YOUNGSTOWN, OHIO.

DESIGN FOR A NONSKID MAT FOR PNEUMATIC TIRES.

Application filed May 7, 1927. Serial No. 21,879. Term of patent 14 years.

To all whom it may concern:

Be it known that I, FRANCIS O. HELTZEL, a citizen of the United States, residing at Youngstown, in the county of Mahoning and State of Ohio, have invented a new, original, and ornamental Design for Nonskid Mats for Pneumatic Tires, of which the following is a specification, reference being had to the accompanying drawing, forming part thereof.

In the drawing—

Figure 1 is a plan view of a nonskid mat for pneumatic tires, showing my new design. Fig. 2 is an edge view thereof.

I claim:

The ornamental design for a nonskid mat for pneumatic tires, as shown.

FRANCIS O. HELTZEL.
